WINDOW SCREEN

Fred M. Sears, Carthage, Mo., assignor to R. L. Platt, C. E. Platt, H. E. Williams, F. B. Williams, and Fred M. Sears, all of Carthage, Mo., doing business as Practo Products Company, Carthage, Mo.

Application April 24, 1947, Serial No. 743,622

5 Claims. (Cl. 160—328)

1

This invention relates to improvements in window screens of the frameless type, having a screen fabric clipped or bound at relative opposite ends respectively by a binding rail for direct attachment to the window frame, and upon tautly spanning the screen fabric, its longitudinal margins are brought into contact with relative rails designated as blind stops protruding inwardly from the window frame.

The invention accordingly consists of a detachable window screen provided with a top and bottom rail only, the top rail being fixed to the window frame by screws, and said bottom rail being composed of two relatively, vertically sliding parts, fitted with holding devices for attachment to the window casing or to any other structure whereby the screen fabric may be put under tension after it has been positioned in the window frame, thus holding it taut with its edges straight and in contacting relation with the front surface of the blind stop of the window frame or to any other support to which the screen is applied.

The principal object of this invention is the provision of a frameless type screen having novel tensioning means whereby the frameless screen may be easily and effectively put under tension and against the blind stop of the window frame with a minimum of effort.

Other objects are simplicity and economy of construction, ease and efficiency of operation, and adaptability for use with any type of frameless screen when it is desirable to tension and maintain the screen fabric in a substantially planar form.

With these objects in view, as well as other objects which will appear during the course of the specification, reference will be had to the drawings wherein—

Figure 1 is a front elevation of a frameless window screen embodying this invention.

Fig. 2 is a sectional view taken on line II—II of Figure 1.

Fig. 3 is a fragmentary enlarged sectional view taken on line III—III of Figure 1.

Fig. 4 is a fragmentary sectional view taken on line IV—IV of Figure 1.

Fig. 5 is a sectional view taken on line V—V of Figure 6.

Fig. 6 is a sectional view taken on line VI—VI of Figure 5.

Fig. 7 is a sectional view taken on line VII—VII of Figure 5.

Fig. 8 is a sectional view taken on line VIII—VIII of Figure 5.

Throughout the several views like reference

2

characters refer to similar parts and the numeral 10 designates a window frame of the common standard type having a sill 12 to which the tensioning means is secured, an upper window stop 5 rail 14 to which the top binding rail of the screen is attached, and side stop rails or blind stops 16 against which the marginal edge portions of the screen fabric is fitted when in the operative position. It will be noticed that the outer faces 10 of the top and side stop rails are in a common plane so that when the screen fabric is tensioned thereagainst it will lie in said plane.

The screen fabric 18 is of substantially rectangular form and is provided at its upper edge with 15 a U-fold 20 which is adapted to be fitted between the spaced apart portions of one leg 22 of the top angled binding bar 24 which is secured to stop bar 14 by means of screws 26. It will be noted that the vertical leg 22 is rebent on itself to 20 form a recess 28 into which the U-fold of the screen 18 is fitted.

The bottom rail 30 comprises an elongated binding rail on which is vertically, slidably mounted an elongated sealing strip 34. Strip 34 25 has stuck-out tongues 36 which respectively extend through vertical slots 38 formed through the body of rail 30. These tongues are pressed against the inner wall of rail 30 to preclude separation of rail 30 and strip 34 and to permit free relative movement thereof. Rail 30 is longitudinally off-set at 40 to form a groove 42 along its inner face. The upper edge portion of rail 30 is rebent on itself to form a downwardly open U-shaped groove member 44 to receive the upturned edge portion 46 of screen 18. Sealing strip 34 is provided with outwardly and downwardly inclined upper and lower flanges 48 and 50 which serve to strengthen the strip and to drain water outwardly from the structure.

40 A screen tensioning means comprises a tensioning lever 52 of substantially channel shape pivotally secured by pivot 54 through one of its flanges 56 and the lower portion of rail 30. The metal of the strip and rail about pivot 54 is offset 45 inwardly to present a recess 53 for the outer head of the pivot 54 as clearly shown in Figure 8. The top portion of the inner end of lever 52 is downwardly recessed at 56' to receive the rounded end of adjusting screw 58 which is operatively 50 mounted in the angled bracket 60 which is pivoted at 62 to the rail 30 as clearly shown in Figures 5 and 7. It will be noted that the metal of rail 30 and bracket 60 about pivot 62 is inwardly recessed to provide a recess 63 to receive the 55 outer head of pivot 62.

A screw eye 64 securely mounted in sill 12 adjustably carries a fulcrum bar 66 of substantially channel shape which is provided with a plurality of vertically spaced apart holes 68 adapted to receive the outer end portion of lever 52 which is turned slightly upwardly at 70 to preclude accidental separation of the parts.

When the screen is to be tensioned the adjusting screw 58 is screwed upwardly a sufficient distance to permit downward movement of the outer end 70 of lever 50 to engage in the proper hole 68 of bar 66 then the operator adjusts screw 58 until the desired tensioning of the screen is obtained. As shown, there is a tensioning means provided at each of the opposite side portions of the screen to obtain proper tensioning pull throughout its entire width.

Brackets 72 secured to sill 12 adjacent the central portion of rail 30 serve to prevent inward distortion of the rail as the tension is applied to the screen.

When the tensioning means are set at both sides of the screen the sealing strip 34 is free to drop by gravity so that its lower flange 50 will close the space between rail 30 and sill 12.

It will be noted from the above description that I have provided a window screen that is so constructed that it may be easily installed or removed from the window and which will at all times maintain the screening under tension over the window opening. Another important feature of this invention is the fact that the screening not only is secured under tension, but also is urged snugly against the window stops, thus efficiently sealing the window opening.

It is obvious that various minor changes may be made in the structure without departing from the spirit of the invention.

What I claim as new and desire to secure by Letters Patent is:

1. A screen for windows comprising a sheet of screen fabric, a binding rail secured to the upper edge of said screen sheet and secured to the upper portion of a window frame, a binding rail secured to the lower edge portion of said screen in spaced relation above the sill of said window frame, a lever pivoted intermediate its ends to said binding rail, a support anchored to said sill, one end of said lever adapted to engage said support, and screw adjusting means carried by said binding rail adapted to engage the other end of said lever, whereby the lever is moved about its pivot to tension said screen.

2. In a window screen of the class described, a sheet of screen secured at its upper edge to a window frame, a binding rail secured to the lower edge of said sheet of screen, a lever pivoted

intermediate its ends to said binding rail, a fulcrum secured to said window frame below said sheet of screen and adapted to receive one end of said lever, and an adjustable means carried by said binding rail to engage the other end of said lever whereby the lever may be adjusted to tension said sheet of screen.

3. In a window screen of the class described, a sheet of screen secured at its upper edge to a window frame, a binding rail secured to the lower edge of said sheet of screen, a lever pivoted intermediate its ends to said binding rail, a fulcrum secured to said window frame below said sheet of screen and adapted to receive one end of said lever, an adjustable means carried by said binding rail to engage the other end of said lever whereby the lever may be adjusted to tension said sheet of screen, and a sealing strip adjustably carried by said binding rail at its outside to close the window opening between said binding rail and the window frame.

4. In a window screen of the class described, a sheet of screen secured at its upper edge to a window frame, a binding rail secured to the lower edge of said sheet of screen, a lever pivoted intermediate its ends to said binding rail, a fulcrum secured to said window frame below said sheet of screen, and adapted to receive and secure one end of said lever against vertical movement, and means carried by said binding rail and having adjustable means operable to engage and move the other end of said lever, whereby the sheet of screen is tensioned.

5. In a window screen of the class described, a sheet of screen secured at its upper edge to a window frame, a binding rail secured to the lower edge of said sheet of screen, a lever pivoted intermediate its ends to said binding rail, a fulcrum secured to said window frame below said sheet of screen, and adapted to adjustably receive and secure one end of said lever against vertical movement, a bracket pivoted to said binding rail, an adjusting screw operatively mounted in said bracket and adapted to engage and move the other end of said lever, whereby to tension said sheet of screen.
